ELECTRIC DISCHARGE LAMP

Alphonse F. Pieper, Brighton, N. Y.

Application June 5, 1940, Serial No. 338,965

2 Claims. (CL 240—1)

This invention relates to an electric discharge lamp, with reference more particularly to a lamp of the general type including an elongated translucent container or bulb having an electrode at each end thereof, enabling the flow of current through a vacuum, gas, or vapor, from one electrode to the other, and it has for its object to eliminate, or reduce to an unobjectionable minimum, the highly undesirable effect that results from the flicker that is present when low frequency alternating currents are used.

In lamps of this general character, particularly to conventional fluorescent bulbs, the effect from flicker is seriously objectionable with alternating current up to fifty cycles and intolerable at twenty-five cycles, due to the making and breaking of the circuit at the electrodes as the direction of current flow is reversed, the flicker being increasingly noticeable as the cycles are decreased in number, and it has been discovered that the flicker is most apparent at the electrode point where the circuit is opened and closed, and barely noticeable at the central part of the tube or container between the electrodes.

In fluorescent bulbs as generally constructed, the electrodes are located at the ends of a glass tube, in which case the flicker which reaches its maximum intensity at the points of the electrodes, is observable directly through the portions of the glass tube directly surrounding the electrodes, and it is a purpose of this invention to obviate or lessen the flicker effect on the eye of an observer by arranging an opaque light obstructing means between the electrodes and the observer, or around the points at which the circuit is opened and closed and maximum flicker occurs, leaving a light emitting area that is restricted to a zone located between the electrodes and not surrounding them, so that it is impossible for light to pass directly from one of the electrodes to an observer and consequently the flicker taking place at the electrode or make-and-break point is completely concealed from view.

To these and other ends, the invention consists in the construction and arrangement of parts that will appear clearly from the following description when read in conjunction with the accompanying drawing, the novel features being pointed out in the claims following the specification.

In the drawing:

Fig. 1 is a view in side elevation of a conventional type of fluorescent bulb, showing applied 55

thereto one practical embodiment of the invention;

Fig. 2 is a sectional view taken longitudinally;

Fig. 3 is an end elevation;

Fig. 4 is a transverse sectional view showing a modified form of the invention, applied to a lamp supported in a housing with a reflecting surface, and

Fig. 5 is a longitudinal sectional view of the same.

Referring more particularly to the drawing, in which like reference numerals refer to the same parts throughout the several views, 1 designates an elongated container of translucent material, consisting in the structure illustrated of a glass tube that is sealed at both ends, and provided with a metallic closure 2 at each end that has a periphery of slightly reduced diameter in comparison with the periphery of the glass tube, while 3 designates the usual socket engaging contacts and 4 are the electrodes connected by a filament 5 that functions to heat the mercury and create the necessary vapor for conducting the flow of current from an electrode at one end of the tube to an electrode at the opposite end of the tube, as usual in this type of lamp.

Owing to the cyclic variations of the current, there is a resulting flicker in the light which is more pronounced with currents of lower frequency, and is observable more noticeably in the immediate vicinity of the electrodes 4 where the circuit is broken as the current reverses. In prior lamps of this type, the light immediately around the electrodes 4 is observable from outside the glass tube or container and is emitted laterally through the glass tube, and it has been discovered that by concealing the electrodes or by placing a light obstructing means around the electrodes so that light cannot pass from immediately around the electrodes laterally through the glass tube, the flicker effect is almost entirely eliminated, or greatly reduced so that it is of negligible consequence.

This result may be attained in any suitable way by guarding or concealing the electrodes so that the light emitting area of the tube is confined to a zone between the electrodes and spaced therefrom endwise of the glass tube or container. In the structure shown, this is accomplished by providing an opaque light sleeve or guard that can be slipped on over the end of the fluorescent tube and retained by frictional engagement therewith. This may include a cylindrical portion 6 of a diameter to surround and closely embrace the outer surface of the glass tube 1, and a portion

1 of reduced diameter that embraces the reduced periphery of the metal closure 2. The sleeve or guard may be of metal or any other suitable material, and the portion 8 extends endwise of the tube 1 somewhat beyond the electrodes 4, as shown, preferably for a distance of approximately one-quarter of an inch beyond the innermost extremity of the electrodes 4 or filament 6, although this distance may vary slightly more or less as determined by the requirements of a lamp of any particular size.

With the light obstructing sleeve in position, it is impossible for light to pass directly from around the electrodes laterally through the glass tube 1, and it is also impossible for an observer to see the light in the immediate vicinity of the contacts 4, owing to the obstruction of the sleeve interposed in such path, and consequently the flicker which occurs to a maximum extent at the contacts 4 cannot be observed.

In Figs. 4 and 5 is shown a modified arrangement applicable to constructions in which a lamp or tube is arranged in a housing affording a reflector behind the lamp. This structure, one of which would be located at each end of the lamp and housing, includes a partition or wall 11 that has a curved edge to conform to the inner curved reflecting surface of the housing, and an opening 12 through which the lamp is inserted into its socket. 13 designates a wall or flange extending laterally from the base of the partition 11 toward the adjacent end of the tube and acting to conceal from view the end portion of the tube behind which the electrodes are located. With this arrangement, the point of maximum flicker at the end of the tube is shut off from any effect on the reflecting surface by the partition 11, and from view of the observer by the wall 13. The device may be held in place by any suitable instrumentalities, as for instance, by lugs 14 formed on the ends of the flange or wall 13 and adapted to be bent over the adjacent edges of the housing.

With such an arrangement, practically no flicker is noticeable through the central portion of the glass tube or the area between the light obstructing sleeves, and it is possible to use currents of sixty cycles, fifty cycles, and even down to forty-five cycles without noticeable or seri-

ously objectionable flicker being observed, which has not been the case with the lamps heretofore employed where the electrodes are located within the glass tube and no guard or obstruction exists between the electrodes and the wall of the glass tube.

It will be understood that the invention may be used in any lamp or fixture on one or more electric discharge bulbs wherever they may be employed. The invention may be carried out in ways other than those specifically disclosed herein, without departing from its essential principle, and this application is intended to cover any changes or modifications that may come within the purposes of the improvement or the scope of the following claims.

I claim:

1. The combination with an electric discharge lamp comprising an elongated translucent hollow container having an electrode at each end thereof, of a transversely curved housing within which said lamp is supported, of opaque light obstructing means including a partition having a curved edge conforming to said curved housing and an opening to receive the lamp, said partition having a lateral wall at its base extending toward the adjacent end of the housing and overlying and concealing from view the end portion of the lamp beyond the partition.

2. The combination with an electric discharge lamp comprising an elongated translucent hollow container having an electrode at each end thereof, of a transversely curved housing within which said lamp is supported, said housing being located above and extending downwardly on both sides of said container, opaque light-obstructing means including a partition located transversely of said housing and having a curved upper edge conforming to the inner surface of the housing, said partition having an opening through which extends the hollow container, the partition having a lateral wall at its lower edge that extends in the plane of the lower edges of said housing and toward the adjacent end of the housing, and means carried by said lateral wall at its opposite edges for securing the same to the bottom edges of the housing and thereby holding the partition in position.

ALPHONSE F. PIEPER.
